UNITED STATES PATENT OFFICE.

CHARLES W. SINKINS, OF LAKE MAHOPAC, NEW YORK.

DESIGN FOR A LAMP.

Application filed July 18, 1923. Serial No. 6,799. Term of patent 14 years.

To all whom it may concern:

Be it known that I, CHARLES W. SINKINS, a subject of the King of England, and a resident of Lake Mahopac, in the county of Putnam and State of New York, have invented a new, original, and ornamental Design for a Lamp, of which the following is a specification, reference being had to the accompanying drawing, forming part thereof, wherein the lamp is distinguished by

means of squared or rectangular braces shown in connection with squared corners and flat panel effects through which the light is adapted to be projected.

The figure is a perspective view of a lamp, showing my new design.

I claim:

The ornamental design for a lamp, as shown and described.

CHARLES W. SINKINS.
